(57) **CLAIM**

The ornamental design for a bogie side frame, as shown and described.

DESCRIPTION

FIG. 1 is a perspective view of a bogie side frame depicting our new design;

FIG. 2 is a side view thereof;

FIG. 3 is a front view thereof;

FIG. 4 is a back view thereof;

FIG. 5 is a top view thereof; and,

FIG. 6 is a bottom plan view thereof.

The broken line portion of the figure drawings is included to show unclaimed subject matter only and forms no part of the claimed design.
